UNITED STATES PATENT OFFICE.

ARMAND H. PEYCKE, OF CHICAGO, ILLINOIS, ASSIGNOR TO AMERICAN STEEL FOUNDRIES, OF CHICAGO, ILLINOIS, A CORPORATION OF NEW JERSEY.

BRAKE-BEAM FULCRUM.

1,335,914.

Specification of Letters Patent.

Patented Apr. 6, 1920.

Application filed December 15, 1917. Serial No. 207,803.

To all whom it may concern:

Be it known that I, ARMAND H. PEYCKE, a citizen of the United States, and resident of Chicago, in the county of Cook and State 5 of Illinois, have invented certain new and useful Improvements in Brake-Beam Fulcrums, of which the following is a specification.

This invention relates to brake beam fulcrums and more particularly to a method of forming same.

The main object of this invention is to simplify and improve the method of forming brake beam fulcrums.

Another object is to provide a brake beam fulcrum adapted to meet the various requirements for successful commercial operation.

Generally speaking, these and other objects are accomplished by providing a brake beam fulcrum by use of the method consisting first in providing a blank with an opening, then bending the blank at the opening to form spaced walls with a recess therebetween for the reception of a supporting member.

The invention is illustrated on the accompanying sheet of drawings in which,

Figure 1 is a plan view of a brake beam fulcrum formed in accordance with my 30 invention;

Fig. 2 is a side elevation of the same showing the fulcrum secured to a brake beam, the latter of which is shown in section;

Fig. 3 is a side elevation, and Fig. 4 is a 35 plan view of the blank from which my brake beam fulcrum is formed;

Fig. 5 is a plan view of the brake beam fulcrum in a formative stage after the blank has been bent intermediate its ends;

Fig. 6 is a side elevation of the arrangement shown in Fig. 5 and also showing an associated brake beam in section;

Fig. 7 is a plan view of the completed 50 brake beam fulcrum after the same has been upset;

Fig. 8 is a side elevation of the completed brake beam fulcrum applied to a brake beam shown in section;

Fig. 9 is a sectional view taken in the 55 plane of line 9—9 of Fig. 7;

Fig. 10 is a plan view, and

Fig. 11 is a side elevation of a modified form of brake beam fulcrum made in accordance with my invention.

5 The various novel features of the inven-

tion will be apparent from the following description and drawings and will be particularly pointed out in the appended claims.

In my improved method of forming a 60 brake beam fulcrum I make use of a single blank 15, which in one operation is stamped from suitable stock and provided with a central elongated opening 16 and four preferably circular openings 17 located near each corner of the blank. This blank, as shown 65 in Figs. 3 and 4, after being heated to a welding temperature is bent intermediate its ends adjacent the opening 16 into the shape shown in Figs. 5 and 6.

It will be understood that suitable dies are 70 used in this operation, there being a suitable mandrel located at the bend to form alined openings 18 in the spaced walls 19 of the fulcrum. These spaced walls form a U-shaped recess or opening for the reception 75 of a supporting member. The ends of the blank are bent into a shape adapted to embrace a brake beam 20. The ends of the blanks, however, are not bent into the final position, as shown in Fig. 8, until it is 80 desired to apply the same to the brake beam. The blank is then upset by suitable movable and stationary die members to the form shown in Figs. 7 and 8 wherein the side walls 19 are made narrower and with 85 greater depth with a web 21^a of reduced size extending therebetween part of the length of the walls 19. The walls also during this operation are provided with outwardly or laterally extending bosses 21 which are provided with key notches 22 for locking in 90 position a pin which may be extended through the openings 18 for connecting the fulcrum to a support or other member.

When the completed fulcrum is actually applied to the brake beam, as shown in Fig. 8, the ends of the fulcrum securely embrace the brake beam and the fulcrum is fixed to the brake beam preferably by rivets 23 which extend through the openings 17 and 95 100 corresponding registering openings in the web of the brake beam 20.

By referring to Figs. 10 and 11, it will be noted that the fulcrum 24 is substantially the same as the one shown in the other figures of the drawing, with the exception that the side walls 25 diverge toward the brake beam and the width of the intermediate flange 26 is increased accordingly.

By means of this method a forged brake 110

beam fulcrum is provided which is adapted to meet the various requirements for successful commercial operation.

It is my intention to cover any modifications coming within the spirit and scope of the following claims.

What I claim is:

1. The method of forming a brake beam fulcrum consisting first in providing a blank with an opening, then bending the blank at the opening to form spaced walls for the reception of a supporting member, and then upsetting said walls to increase the strength thereof against stresses exerted in a given direction.

2. The method of forming brake beam fulcrums, consisting first in providing a blank with an opening intermediate the ends thereof, then bending the blank at the opening to form spaced walls for the reception of a supporting member, and then upsetting said walls to increase their depth for

strengthening the fulcrum against stresses exerted in a given direction.

3. The method of forming a brake beam fulcrum consisting first in providing a blank with an opening, then bending the blank at the opening to form oppositely arranged walls connected by a web, and then upsetting said walls to provide laterally extending bearings thereon.

4. The method of forming a brake beam fulcrum consisting first in providing a blank, then bending the same to form an opening for the reception of a connecting member, and then upsetting said blank adjacent said opening to form a laterally extending bearing boss with a key notch therein.

Signed at Chicago, Illinois, this 8th day of December, A. D. 1917.

ARMAND H. PEYCKE.
